UNITED STATES PATENT OFFICE.

WILLIAM SPARKS, OF JACKSON, MICHIGAN, ASSIGNOR TO THE SPARKS-WITHINGTON COMPANY, OF CLEVELAND, OHIO, A CORPORATION OF OHIO.

LIQUID-FEEDING DEVICE.

1,255,347.

Specification of Letters Patent. Patented Feb. 5, 1918.

Application filed March 16, 1917. Serial No. 155,261.

To all whom it may concern:

Be it known that I, WILLIAM SPARKS, a citizen of the United States, and resident of Jackson, in the county of Jackson, in the 5 State of Michigan, have invented new and useful Improvements in Liquid-Feeding Devices, of which the following, taken in connection with the accompanying drawings, is a full, clear, and exact description.

10 This invention relates to certain improvements in liquid feeding devices for use particularly in supplying liquid fuel to internal combustion engines of automobiles and the like, in connection with which it is very 15 often desirable to have the primary fuel tank carried on the vehicle at a level below the carburetor.

The object of the invention is to provide a device of relatively simple construction 20 and high efficiency in automatic operation with particular relation to the construction of the vacuum tank portion thereof, to which the liquid fuel is elevated as by the suction of the engine, and intermittently discharged 25 therefrom to be fed by gravity to a vaporizing device, as for instance, to the float chamber of a commercial carburetor.

Other objects and advantages relate to the details of construction of the vacuum tank 30 as will hereinafter appear from the following description, taken in connection with the accompanying drawings, in which—

Figure 1 is a somewhat diagrammatic view of the liquid feeding device assembled 35 with a low level fuel tank and an internal combustion engine.

Fig. 2 is a top plan view of the vacuum tank.

Fig. 3 is a cross section on line 3—3, Fig. 1.

40 Fig. 4 is a cross section on line 4—4, Fig. 2.

Fig. 5 is a view similar to Fig. 4 of a slightly modified form of vacuum tank.

As stated, the device is especially designed 45 for use in connection with automobiles embodying internal combustion engines, and the vacuum tank portion thereof may be positioned at any point upon the vehicle to automatically supply fuel to the carburetor, as by gravity, and is usually positioned some 50 distance above the carburetor and above the primary fuel tank.

As shown, the invention comprises a vacuum tank —1— having suitable connection through a pipe —2— with a primary fuel

tank —3—, a second connection, as through 55 pipe —4—, with any source of suction, as the manifold —5— of the engine, and a third connection, as through pipe —6—, with a carburetor —7—.

The invention herein centers about the 60 construction of the vacuum tank —1— which comprises a sheet metal tubular body portion —8— preferably cylindrical in form and having its lower end closed by end wall 65 —9— and divided into two chambers —10— and —11— by an annular transverse wall —13— having a pair of axially extending substantially concentric flanges —14— and —15—, the flange —14— tightly fitting within the tubular body portion and may be 70 secured thereto in any suitable manner, as by soldering, welding, or the like, while the flange —15— is adapted to receive a flanged circular bushing —16— which may, as 75 shown, be internally threaded for the reception of an externally threaded flange —17— upon an elbow-shaped discharge nipple —18— having a valve —19— at its lower end normally closing the opening and 80 slidably mounted upon pins —20— to permit opening of the valve under the weight of fluid when the vacuum is released in chamber —10—, as hereinafter described. Either one, or both, of the pins —20— may be 85 removably secured to nipple —18— to permit movement of the valve from its position across the outlet.

The bushing —16— may support a spider —21— having a passageway aligned with the nipple —18— for the reception of valve stem 90 —22— carrying valve —23— for closing the passageway —24— permitting communication between chamber —10— and fitting —25—, to which fitting the pipe —4— is connected, the latter constituting a suction 95 passage leading from the engine to the chamber, such passage being controlled by valve —23— as actuated by float —26— positioned within chamber —10— and mounted upon and rigidly secured to the valve 100 stem —22—.

The fitting —25— is secured to a cover plate —27— in any suitable manner, as by coacting threads, and for the purpose of rigidly securing the cover —27— to the tubular body —8— a circular angle bar —28— of ring formation, preferably formed of sheet metal with one of its walls comprising

- two thicknesses of the metal, is secured to the upper end of the body —8— with the wall —29— of one thickness telescoped externally with the body —8— and the wall —30— comprising two thicknesses of the metal extending radially and inwardly of the body —8— and chamber —10— to form a seat for packing —31— upon which the cover plate —27— rests, the plate —27— being secured to the angle bar —28— as by screws —32— extending through the plate and the wall —30— of the angle bar.
- The nipple —33— to which pipe 2 is connected, is likewise secured to the cover plate —27— in any suitable way, as by threaded engagement with a flanged bushing —34—, which bushing in turn has a threaded engagement with an annular flange —35— formed upon plate —27—.
- An air inlet conduit or pipe —36— communicates with chamber —10— through the cover —27— and may be secured thereto in any suitable way, as by threaded engagement with annular flange —37— formed thereon. An annular disk —38— may be provided, secured to the inner surface of cover plate —27— for forming a seat for an inwardly closing valve —39— controlling communication between conduit —36— and chamber —10—. For the purpose of operating valve —39— reversely in accordance with the operation of valve —23—, a U-shaped lever —40— is provided having its opposite ends pivoted upon flanges —41— and —42— extending downwardly in chamber —10— and preferably formed integral with a strip —43— of sheet metal or the like secured to the interior surface of cover plate —27— and having suitable openings registering with the conduits communicating with nipples —25— and —33—.
- The lever —40— is provided with an opening —44— at one side of the central portion of its base through which opening valve stem —45— loosely extends, the valve stem being provided with opposite enlargements —46— and —47— constituting stops limiting the movement of the lever along the stem and permitting such limited movement without movement of the valve.
- The valve stem —22— is provided with a disk —48— mounted thereon at a proper position relative to the pivot of lever —40—, to which disk one end of spring —49— is secured, the opposite end of the spring being secured to the lever —40— preferably at a point substantially centrally of the base of the lever. A second spring —50— is provided, likewise secured to the disk —48— at a point preferably diametrically disposed with respect to the securement of spring —49—, the opposite end of spring —50— being secured to a depending flange —51— formed upon the end of plate —43—.
- Preferably at least one of the flanges

—42— is provided with a finger —52— depending, as shown, a distance somewhat less than the downward extent of the flange and against which an arm of lever —40— is adapted to abut in its upward movement to limit the movement of the lever in opening valve —39—. In Fig. 4, the valve —39— is illustrated as closed, whereas, in Fig. 5, the valve is shown in its open position.

Suitable connection is made between chamber —11— and the atmosphere, as by pipe —53— engaged with and penetrating wall —13— and extending through wall —30—, packing —31— and cover plate —27—, and secured to and penetrating the wall of conduit —36— so that atmospheric pressure is substantially maintained within chamber —11— to permit the free discharge of liquid therefrom by gravity.

The lower end —9— of the body —8— may be provided with a drainage or discharge faucet —54— secured in any suitable manner, to permit the withdrawal of liquid therefrom at will, and a suitable fitting —55— to which pipe —6— is connected, leading to the carbureter. The end —9— may be pressed in suitable form, as shown at —56—, to constitute a substantially horizontal seat for bushing —57— to which the fitting —55— may be secured.

Preferably the fuel inlet through nipple —33— is provided with a suitable screen, in this instance a cup-shaped screen —58— having a flanged edge, the flange positioned between the plate —43— and bushing —34— to rigidly secure the screen in desired position.

The operation of the device will be readily understood. When the tank is empty, the float —26— will lie in such a position within chamber —10— as to open valve —23— permitting the passage of the suction from a suitable source through pipe —4— to chamber —10—, the vacuum thereby produced in chamber —10— elevating the liquid from tank —3— through pipe —2— to the chamber, the valve —39— being held in closed position by spring —49— acting upon lever —40—. When sufficient liquid has been thus elevated into chamber —10— so as to raise the float to a point at which disk —48— moves to a position above the pivot of lever —40— upon the flanges —42—, the tension of spring —49— will snap lever —40— upwardly about its pivot to open valve —39— and permit substantially free communication of chamber —10— with the atmosphere.

At this point the valve —23— will be either closed or substantially closed, the vacuum in chamber —10— will be substantially neutralized to permit the discharge of the fluid from nipple —18— under the action of gravity. When the discharge has been effected to such an extent that valve —39—

is closed by tension of spring —49—, as when disk —48— moves a sufficient distance below the pivot of the lever upon the flanges —42— and the valve —23— is unseated, then the suction will again be applied to chamber —10—, vacuum produced therein, and the operation repeated. The fuel discharges freely from chamber —11— to any suitable vaporizing device, as carburetor —7—, through nipple —55—, pipe —53— maintaining atmospheric pressure in said chamber.

The spring —50— serves to counter-balance the spring —49— to effect uniform and direct reciprocation of valve stem —22— without binding, the springs neutralizing each other so far as their action upon valve —23— and valve stem —22— is concerned.

The construction of the tank shown in Fig. 5 varies slightly from that shown in Fig. 4, in that the body —8— is formed of two parts —59— and —60— having their meeting edges outwardly flanged and with transverse wall —61— secured therebetween, suitable packing being interposed as shown. The nipple —18— is secured directly to an annular flange upon the wall —61— and the spider —62— is of dished formation, having its end portions resting upon said transverse wall. The upper end of the part —59— is outwardly flanged at —63— and the plate —27— is secured to this flange, as by bolts —64—, suitable packing being interposed between the parts as shown.

The pipe —65— is positioned outside the chamber —10— and extends through the plate —27— and flange —63— and through the flange formed on part —59—, to which the flange on part —60— is secured, and through the transverse wall or plate —61—, the part —60— being provided with an offset portion —66— permitting communication between the pipe —65— and chamber —11—.

The connection of faucet —54— and nipple —55— to the lower end wall of chamber —11— differs only in exact relative position of the parts, and in the fact that, the end wall being horizontal and substantially flat, the indentation —56— is omitted. Otherwise the construction and operation of the tanks is substantially the same, that shown in Fig. 4 being preferred by reason of economy and permanency in construction.

Although I have shown and described particular forms of tanks and particular constructions embodied therein, and certain details of each of the same as perhaps preferable, yet I do not desire to limit myself to any specific form or construction except as specifically indicated in the claims hereto appended, as various changes may be made in the details of each of the same without departing from the spirit and scope of the invention.

What I claim is:—

1. In an apparatus of the character described, a receptacle having a suction connection, a liquid inlet connection and an atmosphere connection, a valve controlling one of said connections and having an elongated stem, a float mounted on said stem and actuating said valve, a second valve controlling another of said connections, a lever pivoted within said chamber and connected to the second valve, and a spring connected to the lever and having a portion moving with said float to opposite sides of the pivotal axis of the lever.

2. A device for the purpose indicated comprising a receptacle formed with two chambers, valved means of communication between the chambers, the upper chamber provided with a suction connection, a liquid inlet and an atmosphere connection, a valve controlling one of said connections and having an elongated stem, a float mounted on said stem and actuating said valve, a second valve controlling another of said connections, a lever pivoted within said chamber and connected to the second valve, and a spring connected to the lever and having a portion moving with said float to opposite sides of the pivotal axis of the lever.

3. In an apparatus of the character described, a receptacle having a suction connection, a liquid inlet connection and an atmosphere connection, a float in said receptacle, a valve operated by the float and controlling one of said connections, a second valve controlling another of said connections, a lever pivoted within the chamber and connected to the second valve, a spring connected to the lever and having a portion moving with said float to opposite sides of the pivotal axis of the lever, and a second spring having one end moving with the float and its opposite end supported in stationary condition within the chamber to counter-balance the lateral tension of the first-named spring upon the float.

4. A device for the purpose indicated, comprising a receptacle, a liquid inlet, a suction connection, a valve controlling the suction connection, said valve having an elongated stem, a float mounted upon said stem to operate the valve, an atmosphere inlet, an atmosphere valve controlling the atmosphere inlet, a lever engaged with said atmosphere valve and having a stationary pivot, and a spring having one end connected to the lever and its opposite end moving with the float to operate the lever and thereby actuate the atmosphere valve.

5. A device for the purpose indicated, comprising a receptacle, a liquid inlet, a suction connection, a valve controlling the suction connection, said valve having an elongated stem, a float mounted upon said stem to operate the valve, an atmosphere in-

let, an atmosphere valve controlling the atmosphere inlet, a U-shaped lever engaged with said atmosphere valve and having a stationary pivot, and means actuated by the 5 movement of the float for operating said lever to actuate the atmosphere valve.

6. A device for the purpose indicated, comprising a receptacle, a plate carried by the receptacle and having a pair of spaced 10 flanges depending within the receptacle, a U-shaped lever having its ends respectively pivoted upon said flanges, an atmosphere inlet to said receptacle, an atmosphere valve controlling said inlet and having its stem 15 engaged with said lever, a suction connection with the receptacle, a valve controlling such connection and having a float mounted upon its stem, and a spring having one end connected to move with the float and its op- 20 posite end connected to the lever at a point beyond the connection of said atmosphere valve stem to the lever.

7. A device for the purpose indicated, comprising a receptacle, a plate carried by 25 the receptacle and having a pair of spaced flanges depending within the receptacle, a U-shaped lever having its ends respectively pivoted upon said flanges, an atmosphere inlet to said receptacle, an atmosphere valve 30 controlling said inlet and having its stem engaged with said lever, a suction connection with the receptacle, a valve controlling such connection and having a float mounted upon its stem, a spring having one end connected 35 to move with the float and its opposite end connected to the lever at a point beyond the connection of said atmosphere valve stem to the lever, and a second spring having one end connected to move with the float 40 and counter-balance the effect of the first-named spring upon the float.

8. A device for the purpose indicated comprising a receptacle having a float chamber, a suction inlet, a valve for said inlet 45 having an elongated stem, a float mounted upon the stem, springs having their ends secured to the stem diametrically thereof and at a point above the float, one of said springs having a stationary connection for its op- 50 posite end, a U-shaped lever pivoted within the chamber, the other spring having its opposite end connected to the base of the U-shaped lever, an atmosphere inlet, an atmosphere valve for said inlet, said atmos- 55 phere valve having its stem engaged with said lever intermediate the point of connection of the spring and the pivot of the adjacent arm of said lever.

9. A device for the purpose indicated, 60 comprising a cup-shaped body, a plate extending transversely of the body and having a pair of annular flanges, the flange of larger diameter in contact with the interior wall of the body, an outlet nipple connected to 65 the inner flange, a valve for said nipple, and

a cover plate secured to the upper end of the cup-shaped body, said cover plate provided with a suction connection, an atmosphere inlet and a liquid inlet, and float operated means for controlling the two first-named 70 connections.

10. A device for the purpose indicated, comprising a cup-shaped body, a plate extending transversely of the body and having a pair of annular flanges, the flange of larger 75 diameter in contact with the interior wall of the body, an outlet nipple connected to the inner flange, a valve for said nipple, an angle bar secured to the upper end of the cup-shaped body and having a portion projecting radially and inwardly of said body, and a cover plate secured to the angle bar, said cover plate provided with a suction connection, an atmosphere inlet and a liquid inlet, and float operated means for controlling 80 the two first-named connections. 85

11. A device for the purpose indicated comprising a receptacle having a suction connection, a liquid inlet, an atmosphere connection, a valve for the suction connection 90 having an elongated stem, a float mounted on said stem to operate the valve, an atmosphere valve, a lever provided with a stationary pivot within the receptacle and having a lost motion connection with the atmosphere valve, a spring connected to the stem of the suction valve and to the lever and movable with said stem to positions upon opposite sides of the pivot of the lever whereby the atmosphere valve is instantly 95 and completely opened at a predetermined 100 position of said stem.

12. A device for the purpose indicated comprising a receptacle formed with an upper and a lower chamber, a conduit forming means of communication between the chambers, a flap valve controlling said conduit and opening outwardly into the lower chamber, the upper chamber provided with a suction connection, a liquid inlet and an atmosphere inlet, a valve controlling the suction connection, said valve having an elongated stem, a float mounted upon said stem to operate the valve, an atmosphere valve controlling the atmosphere inlet, a lever pivoted within the chamber and engaged with said atmosphere valve, and a spring having one end connected to the lever and its opposite end connected to the stem of the valve controlling the suction connection. 115

13. A device for the purpose indicated comprising a receptacle, a plate carried by the receptacle and having a flange depending within the receptacle, a lever having its end pivotally connected to said flange, an atmosphere inlet to said receptacle, an atmosphere valve controlling said inlet and having its stem engaged with said lever, a suction connection with the receptacle, a valve controlling such connection and having a float 125 130

mounted upon its stem, and a spring having one end connected to said stem and its opposite end connected to the lever.

14. A device for the purpose indicated comprising a receptacle, a plate carried by the receptacle and having a flange depending within the receptacle, a lever having its end pivotally connected to said flange, an atmosphere inlet to said receptacle, an atmosphere valve controlling said inlet and having its stem engaged with said lever, a suction connection with the receptacle, a valve controlling such connection and having a float mounted upon its stem, a spring having one end connected to said stem and its opposite end connected to the lever, said plate having a second depending flange, and a second spring having one end connected to said stem and its opposite end connected to said second flange to counter-balance the lateral tension of the first-named spring upon said stem.

15. A device for the purpose indicated comprising a receptacle, a plate carried by the receptacle and having a flange depending within the receptacle, a lever having its end pivotally connected to said flange, an atmosphere inlet to said receptacle, an atmosphere valve controlling said inlet and having its stem engaged with said lever, a suction connection with the receptacle, a valve controlling such connection and having a float

mounted upon its stem, and a spring having one end connected to said stem and its opposite end connected to the lever, said plate 35 having a finger lying in the path of movement of the lever.

16. A device for the purpose indicated comprising a receptacle formed with two chambers, valved means of communication 40 between the chambers, the upper chamber provided with a suction connection, a liquid inlet and an atmosphere connection, a valve controlling one of said connections and having an elongated stem, a float mounted on 45 said stem and actuating said valve, a second valve controlling another of said connections, a lever pivoted within said chamber and connected to the second valve, a spring connected to the lever and having a portion 50 moving with said float to opposite sides of the pivotal axis of the lever, and a second spring having one end moving with the float and its opposite end supported in stationary condition within the chamber to 55 counterbalance the lateral tension of the first-named spring upon the float.

In witness whereof I have hereunto set my hand this 27th day of Feb., 1917.

WILLIAM SPARKS.
